STOWAGE BRACKET FOR FLOATS ON SHIPBOARD

Filed April 28, 1944

ARTHUR *INVENTOR.*
N. ANDERSON.

BY Percy Freeman

ATTORNEY.

UNITED STATES PATENT OFFICE

2,425,911

STOWAGE BRACKET FOR FLOATS ON
SHIPBOARDArthur N. Anderson, Brooklyn, N. Y., assignor to
Helen M. Anderson, Brooklyn, N. Y.

Application April 28, 1944, Serial No. 533,139

1 Claim. (Cl. 214—10.5)

1

This invention relates to apparatus for supporting stacked floats on the deck of a ship.

An object of this invention is to provide float-supporting apparatus of the character described having means normally permitting the floats to be floated off the deck in case the ship sinks.

Another object of this invention is to provide means for stacking a pile of floats one above the other in spaced relation, permitting air to circulate between the floats and thereby preventing deterioration due to dampness.

Yet another object of this invention is to provide stacking means of the character described which will support a number of floats one above the other in spaced relation while permitting the floats to be readily taken off the pile, and being further provided with means to lash the floats to the deck in case of rough seas, the lashing means including furthermore a pelican hook whereby the lash may be easily released in case of emergency.

Yet another object of this invention is to provide a strong, rugged and durable means for supporting a plurality of floats one above the other, which shall be inexpensive to manufacture, easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawings, in which are shown various possible illustrative embodiments of this invention,

Fig. 1 is a vertical side view of a stack of floats supported with supporting means embodying the invention.

Fig. 2 is a top plan view thereof.

Fig. 3 is a top plan view of one of the separators.

Fig. 4 is a cross-sectional view taken on line 4—4 of Fig. 1.

Fig. 5 is an enlarged detail view of a part of the structure shown in Fig. 1.

Fig. 6 is a partial perspective view of floats and separators therebetween and illustrating a modified form of separator.

Referring now in detail to the drawing, 10 designates a float stack embodying the invention. The same comprises a plurality of floats 11 supported on the deck 12 of the ship by means

2

of supporting apparatus 15 embodying the invention. The floats 11 may be of usual construction. Each comprises an annular ring 11a of balsa wood or the like material, of substantially circular cross-section. The ring 11a has parallel side portions 11b interconnected by semi-annular end portions 11c. Each float is provided with a bottom 11d attached to the ring 11a by means of a fabric web or sheet 11e. It will be noted that the floats 11 are supported by apparatus 15, one above the other in spaced aligned, horizontal relation.

The supporting means 15 comprises a pair of parallel similar bottom brackets 16 attached to the top of deck 12. Each bracket 16 comprises an elongated member formed with a pair of spaced notches or grooves 17 in its upper surface for the purpose hereinafter appearing.

At the outer ends of member 16 are flanges 18 receiving bolts or screws 19 for attaching the brackets to the deck. The distance between the center lines of grooves 17 is substantially equal to the distance between the center lines of the side portions 11b of the floats 11.

It will now be understood that the bottom float 11 rests on the brackets 16 with the side portions 11b of said float received within the notches 17. The height of notches 17 is preferably substantially equal to half the height of a float so that the upper portions of the bottom float 11 projects above the brackets 16.

In between each pair of adjacent floats 11a is a spacing member 20. Each spacing member comprises two pair of similar spacing blocks 21 interconnected by cross members 22 and 23. The rods 22 and 23 may be welded together or otherwise interconnected where they cross as at 24. The blocks 21 are located at the ends and sides of the floats whereby rod 22 is longer than the transverse rod 23. Each spacing block 21 has a notch 25 to contact a lower float and a notch 27 to contact the upper float. The outer ends or surfaces 28 of the blocks are preferably substantially in line with the center lines of the sides of the floats. The inner surface 29 of the blocks are preferably spaced inwardly of the inner rims of the floats. The spacing blocks 21 thus keep the floats spaced from one another so as to prevent deterioration or rotting due to dampness. There is no spacing member at the top of the stack so that the top float may be taken off, and thereafter the top spacing member 20 may be taken off, and so on.

Normally in calm seas the floats need not be lashed down to the deck. If the ship is sunk, the

floats will float off freely in the water. Means is provided, however, to lash the stack of floats down to the deck in case of heavy seas. To this end, there is attached to one end of each bracket 16 a pad eye 40. Hooked onto each pad eye 40 is a strap 41 which extends upwardly and over the stack of floats and then downwardly on the other side of the stack. Attached to the opposite ends of the brackets 16 are pad eyes 42 to which are pivoted pelican hooks 43 engaging the free ends of strap 41. The pelican hooks may be readily released in case of emergency.

In Fig. 6, there is shown a modified form of spacer between the floats. The spacer 20 shown in Fig. 3, is replaced by separate spacing blocks 60 of substantially H cross-section. Each spacing block 60 has substantially semi-cylindrical notches 61 in its upper and lower surfaces to receive the underside and upperside of a pair of floats above and below the block respectively. The blocks 60 are not interconnected but the blocks are preferably distributed at the ends and sides of the floats.

It will be understood that the floats may easily be floated off the blocks in case the ship is torpedoed.

It will thus be seen that there is provided a device in which the several objects of this invention are achieved, and which is well adapted to meet the conditions of practical use.

As various possible embodiments might be made of the above invention, and as various changes might be made in the embodiments

above set forth, it is to be understood that all matter herein set forth or shown in the accompanying drawing is to be interpreted as illustrative and not in a limiting sense.

Having thus described my invention, what I claim as new and desire to secure by Letters Patent, is:

Spacing members for use in stowing a plurality of floats on shipboard in spaced, stacked relation, each of said spacing members comprising crossed members and spacer blocks located at the ends of each arm of said crossed members.

ARTHUR N. ANDERSON.
